FILLING END PARTING MECHANISM

Edward C. Nichols, Upton, Mass., assignor to
 Draper Corporation, Hopedale, Mass., a corpora-
 tion of Maine

Application February 25, 1941, Serial No. 380,505

8 Claims. (Cl. 139—263)

This invention pertains to automatic filling replenishing looms and more particularly relates to mechanisms for parting the incoming filling ends of such looms.

Looms of the type above referred to commonly include a reciprocating lay with a shuttle box at the replenishing end thereof, filling replenishing mechanism including a magazine containing a plurality of reserve filling carriers and a filling end holder to which the filling ends of the reserve carriers are attached, mechanism such as a temple thread cutter for parting the filling ends adjacent the cloth selvage and mechanism for parting the filling attached to the outgoing filling carrier. In addition, such looms may include mechanism for removing from the loom loose pieces of filling ends.

The filling replenishing mechanism in its operation incidentally forms an incoming filling end extending from the cloth selvage to the filling end holder and an outgoing filling end extending from the cloth selvage to the parting and clamping mechanism which operates at the time of transfer to clamp and sever the outgoing filling end from the exhausted filling carrier.

Upon severance of the outgoing and incoming filling ends at the cloth selvage, the outgoing filling end is free to fall downwardly away from the lay, or may be completely removed from the loom by the thread remover if one is provided. The incoming filling end is still attached to the filling end holder and may become entangled in the moving parts of the loom or, if a thread remover is provided, cannot be completely removed from the loom by the thread remover until it is parted from the filling end holder.

It is essential for the proper operation of the loom that the incoming filling end remain attached to the filling end holder for a plurality of picks after the operation of the replenishing mechanism. Prior to the present invention, release of these ends from the filling end holder has been accomplished manually. In so far as I am aware no means have ever been provided heretofore for parting the incoming filling end adjacent the magazine after it has been formed by the operation of the replenishing mechanism.

Accordingly, it is a principal object of this invention to provide an automatic filling replenishing loom including replenishing mechanism comprising a magazine containing a reserve filling carrier, a filling end holder to which the filling end of the reserve carrier is attached, a temple thread cutter, and a filling end parting and clamping mechanism as aforesaid, and a

thread parter for parting the incoming filling end adjacent the filling end holder, said thread parter shall be so constructed and arranged as to part each newly formed incoming filling end a plurality of picks after the operation of the replenishing mechanism forming the same.

This and other objects of the invention are accomplished in the construction illustrated on the accompanying drawings, wherein:

Fig. 1 is a perspective view of the replenishing side of an automatic loom having the preferred embodiment of my invention applied thereto;

Fig. 2 is a plan view of the parting mechanism of my invention; and

Fig. 3 is a side view of the mechanism shown on Fig. 2.

The drawings show but parts of a loom, the parts and mechanisms not shown being of usual construction and forming no part of the present invention.

The drawings show a reciprocating lay beam 1 having a reed 2 and a shuttle box 3 mounted thereon, a right hand side frame 4 and a breast beam 5 on which is mounted the replenishing mechanism. The replenishing mechanism may be of any usual construction wherein is provided a magazine adapted to contain a plurality of reserve filling carriers and having means for holding the ends of the filling on the carriers.

The particular mechanism shown is of the usual rotary battery type. Only a portion of the replenishing mechanism is shown, the portion shown includes the transerrer stub shaft 6, magazine 7 holding a plurality of reserve filling carriers or bobbins 8, a thread guide disc 9, a filling end holder 10, to which are attached the ends of the filling on the bobbins 8 and means for rotating the magazine to successively bring the reserve filling carriers 8 into transfer position, including ratchet 10' and feed pawl 11'.

The loom also is shown as equipped with a temple thread cutter indicated generally at 11, a parting and clamping mechanism for parting and clamping the outgoing filling end indicated generally at 12 and a thread remover for removing loose pieces of filling ends indicated generally at 13.

The temple thread cutter may be of the usual construction and may comprise a lay actuated cutter 14 mounted on the temple 15.

The thread remover may be similar to the thread remover described and claimed in the co-pending application of Carl D. Brown, et al., Serial No. 331,844 filed April 26, 1940, now Patent No. 2,233,373, and may comprise a bracket 16

fixed to stub shaft 6 and carrying a conduit 17, and a reciprocating rod 18 pivotally attached to the lay beam as at 19 for feeding the loose filling ends into and along the conduit, all as more fully described in the above referred to co-pending application of Carl D. Brown et al.

The parting and clamping mechanism for parting the outgoing filling end adjacent the shuttle may be similar to that described and claimed in the patent to Northrop No. 2,028,560 granted January 21, 1936, and may comprise parting and clamping blades 20 mounted on a carrier 21 which reciprocates in a guide member 22 mounted on a bracket 23 attached to the stub shaft 6. Means are provided for opening and closing the parting and clamping blades including a blade operating member 24 and a pivoted cam 25 mounted on a bracket 26; and means are provided for moving the carrier and the parting and clamping blades toward and from the shuttle box, including a pin 27 mounted on carrier 21 and engaging a swinging bracket 28, all as more fully described in the above referred to patent to Northrop.

A shuttle 29 is shown in the shuttle box 3. Shuttle 29 carrying the filling supply is picked from side to side along the lay beam 1 by suitable means which may include a picker stick 30. As the shuttle is thus picked, it lays filling thread in the shed S which filling thread is beaten into the fell of the cloth C by the reed 2. When the filling supply in the shuttle is substantially exhausted, a fresh supply is provided by the automatic replenishing mechanism.

The transfer of a bobbin 8 to the shuttle 29 and the subsequent picking of the shuttle results in the formation of a length of filling thread which extends from the holder 10 through the shed S. The subsequent beating in of the portion of this thread which is in the shed leaves the end f projecting from the cloth selvage to the holder 10. This filling end is known in the art as the incoming filling end.

The operation of the replenishing mechanism results in the formation of another filling end f' projecting from the cloth selvage to the outgoing or exhausted bobbin in the shuttle and is known as the outgoing filling end. Thus the incoming and outgoing filling ends are formed incidental to the operation of the replenishing mechanism.

The outgoing filling end f' is parted adjacent the shuttle eye at the time of transfer by the parting and clamping blades 20. These blades part and clamp the outgoing filling end and withdraw it from the shuttle box.

The outgoing filling end f' and the incoming filling end f are severed adjacent the cloth selvage by the temple thread cutter 14 a few picks after transfer. The reciprocating rod 18 of the thread remover catches the outgoing and incoming filling ends after they have been severed by the temple thread cutter and feeds them into and along the conduit 17. Means are provided in the conduit for preventing retrograde movements of the filling ends as the rod 18 moves. Upon release of the outgoing filling end by the parting and clamping mechanism, the loose piece of outgoing filling is completely fed through the conduit 17 and removed from the loom. The incoming filling end, however, has one end attached to the holder 10 and cannot be completely fed through the conduit 17 and removed from the loom until it has been parted from the end holder 10.

I provide a thread parting mechanism for

parting the incoming filling end f adjacent the filling end holder 10. Such mechanism may comprise an arm 31 adjustably attached to the upper rear end of the bracket 23 by means of bolt 32. Arm 31 may be formed of a metallic strip or other suitable material bent to an approximately Z shape, as best seen on Fig. 2, with its free end projecting beyond and adjacent the inner edge of the thread guide disc 9. A plate 33 having a V-shaped slot 34 in its rear end is fixedly attached to arm 31 as by rivets 35. Rounded projections 36 and 37 project inwardly from the upper and lower edges respectively of slot 34 and adjacent the outer end thereof. The rounded projections 36 and 37 serve to guide the incoming filling thread into the slot 34 and to prevent the loom operator's finger from getting into the slot. A cutting blade 38 is fixedly attached to plate 33 and positioned so that its lower cutting edge 39 projects slightly below the upper edge of slot 34. A second cutting blade 40 is fixedly attached to plate 33 and positioned so that its upper cutting edge 41 projects slightly above the lower edge of slot 34 all as best seen on Fig. 3.

Since it is essential that the incoming filling end remain attached to the holder 10 for at least several picks after transfer it is necessary that the parting mechanism for parting the incoming filling end be so arranged as to part the incoming filling a plurality of picks after transfer. This result is accomplished by the mechanism of my invention, for the plate 33 is so located relative to the thread guide disc 9 that immediately after transfer the rotation of the battery to bring the next bobbin into transfer position (which action is part of the replenishing operation) will bring the incoming filling end f' into the slot 34 where the projections 36 and 37 tend to hold it. While in slot 34 the incoming filling end f is severed either by the vibration of the loom or upon the next operation of the transfer mechanism. Thus it is seen that each newly formed incoming filling end is parted adjacent the filling end holder at least a plurality of picks after its formation.

Having thus fully described the preferred embodiment of my invention, I claim:

1. In an automatic filling replenishing loom of the type incidentally forming incoming and outgoing filling ends, the combination of replenishing mechanism including a rotary battery carrying a plurality of reserve filling carriers, a filling end holder to which the filling ends of said reserve filling carriers are attached, means for parting said incoming and outgoing filling ends adjacent the cloth selvage, means for parting the outgoing filling end adjacent the outgoing filling carrier, and stationary means cooperating with said rotary battery for parting the incoming filling end between said rotary battery and said filling end holder a plurality of picks after said incoming filling end has been formed.

2. In a loom of the type which successively replaces the running filling carrier with a fresh filling carrier upon the substantial exhaustion of the former by transfer from a rotary magazine containing a plurality of reserve filling carriers thereby incidentally forming incoming and outgoing filling ends, the combination of means for parting the outgoing filling end adjacent the exhausted filling carrier upon transfer, means for parting the incoming and outgoing filling ends adjacent the cloth selvage a plurality of picks after transfer, and stationary means cooperating with said rotary magazine for parting the incom-

ing filling end at the said rotary magazine a plurality of picks after transfer.

3. In an automatic filling replenishing loom of the type incidentally forming incoming and outgoing filling ends, the combination of replenishing mechanism including a battery-carrying a plurality of reserve filling carriers, a filling end holder spaced apart from said battery and toward the outside of the loom to which the filling ends of said reserve filling carriers are attached, means for parting said incoming and outgoing filling ends at the cloth selvage, means for parting the outgoing filling end at the outgoing filling carrier, means for parting the incoming filling end between said battery and said filling end holder a plurality of picks after said incoming filling end has been formed and means for moving the incoming filling end into engagement with said parting means.

4. In an automatic replenishing loom of the type incidentally forming incoming filling ends, the combination of a magazine adapted to hold a plurality of reserve filling carriers, a holder to which the filling ends of said carriers are attached and means for successively parting each incoming filling end adjacent said holder a plurality of picks after the formation thereof, said means including a member having a stationary V-shaped opening with cutting edges therein.

5. In an automatic replenishing loom of the type incidentally forming incoming filling ends, the combination of a magazine adapted to hold a plurality of reserve filling carriers, a holder to which the filling ends of said carriers are attached and means for successively parting each incoming filling end between said magazine and said holder a plurality of picks after the formation thereof, said means including a member having a stationary V-shaped opening therein, the upper and lower edges of said opening forming cutting edges.

6. In an automatic filling replenishing loom the combination of replenishing mechanism including a magazine adapted to hold a plurality of reserve filling carriers, a holder to which the ends of the filling of the reserve carriers are attached, and parting means including a stationary member having a V-shaped opening therein, said means being so constructed and arranged as to successively part each of said 10 filling ends adjacent said holder a plurality of picks after transfer of the filling carrier to which said filling end is attached.

7. A thread parter for looms of the type including a replenishing mechanism comprising a magazine, a thread guide and a filling end holder, said parter comprising a Z-shaped member having one end fixedly attached to a stationary part of the loom, the free end of said member extending beyond and adjacent to said thread guide, a plate fixedly secured to the free end of said member, said plate having a V-shaped opening therein, and a pair of cutting blades fixed to said plate, one of said blades projecting above the lower edge of said opening and the other of said blades projecting below the upper edge of said opening.

8. In an automatic filling replenishing loom of the type incidentally forming incoming and outgoing filling ends, the combination of means for parting the incoming and outgoing filling ends adjacent the cloth selvage, means for parting the outgoing filling end adjacent the outgoing filling carrier, stationary means for parting the incoming filling end at the replenishing mechanism, and means constructed and arranged to cooperate with said parting means to part said incoming filling end a plurality of picks after formation thereof by moving said filling thread into engagement with said parting means.
